UNITED STATES PATENT OFFICE

THEODORE J. RADKE, OF OAK PARK, ILLINOIS.

AUTOMATIC WATER-HEATER.

1,204,313.

Specification of Letters Patent.

Patented Nov. 7, 1916.

Application filed June 19, 1915. Serial No. 35,057.

To all whom it may concern:

Be it known that I, THEODORE J. RADKE, a citizen of the United States, residing at Oak Park, in the county of Cook and State 5 of Illinois, have invented certain new and useful Improvements in Automatic Water-Heaters, of which the following is a specification.

This invention relates to that class of 10 automatic water heaters for domestic and like uses, wherein the fuel, usually a gas, is automatically supplied to and cut off from the burners through the operation of the water control at the discharge end of the system.

A particular object of this invention is 15 to provide means for regulating the inflow of cold water by the temperature of the water flowing through the heater and at the same time automatically controlling the gas 20 supply to the burners.

A further particular object is to provide 25 an automatic means for obtaining water of any desired temperature at the discharge end of the system.

Another particular object is to provide a 30 thermostatically controlled mechanism for operating the cold water inlet valve independently of the automatic gas control to the main burners.

These and other objects hereinafter set 35 forth are attained by the means illustrated in the accompanying drawing, in which is shown a vertical sectional view taken centrally through the improved apparatus.

In the drawing similar reference numerals 40 designate like parts.

The casing of the heater, comprises a 45 burner section 10 mounted upon a base 11, a double wall heater section 12 supported by said burner section, and a cap section 13 which is supported on top of said heater section.

Base 11 embodies a basin 14 and an outer 50 ring 15 provided with a flange 16 adapted for engagement within the upstanding edge 17 of the basin. The outer ring 15 is also formed with a flanged seat 18 on which the burner section is positioned.

Basin 14 is formed with a central support 19 into which is fixed a depending 55 extension of a two-way coupling 20, and se-

cured in the upper end of said coupling and extending upwardly through said heater section, is a vertical water tube 21 to the top 55 end of which is secured a combined coupling and support 22. The top end of the coupling 22 is apertured at 23 to receive the threaded lower end of a bolt 24 which is provided with a flange 25 adapted for engagement with the top surface of coupling 22.

Cap section 13 is provided with a flue pipe 60 collar 26 in which is secured a spider 27 having a central apertured hub which engages 65 over the upper end of bolt 24, and the lower edge of said cap section is flanged, as shown at 28, to engage over the top edge of the heater section.

From the above description, it will be 70 seen that the basin 11 and cap 13 are directly connected together by a central tie which is formed of coupling 20, water tube 21, coupling 22, and bolt 24, and by tightening the nut 29 on the top end of the bolt 24 above 75 the spider 27, the several body sections and base and cap are drawn tightly together and retained rigidly in position.

At the base of flue pipe collar 26 is formed 80 an inwardly extending flange 31, and adjacent said flange and above the same is provided a series of apertures 32 extending through the wall of the collar. Thus, when the heater is in position for operating with the pipe collar connected to a suitable outlet, any backward draft from the outlet will 85 be deflected outwardly through aperture 32 and from the interior of the heater by the flange 31.

Secured to the water tube 21, in any suitable manner, is a plurality of supporting spiders 33 which are adapted to support the heater case 34, which may be made of a continuous pipe or several sections connected together forming a continuous conduit, as 90 set forth in my Patent No. 1,070,529. The lower end of the heater coil is connected to coupling 20 by a pipe section 35, including a three-way coupling 36 which is provided 95 with a cock 37 for draining said coil when 100 desired.

On the interior of the central water tube 21 and extending its full length thereof, is located a thermostatic member 38 whose

lower end is fixed in the central support 19 of the basin 14 and whose upper end passes through a stuffing box 39 on the coupling 22. Coupling 22 is apertured at 40 to receive the 5 short end 41 of a lever 42 which is pivoted at 43 to said coupling. The long end of this lever 42 passes through an aperture 44 in the wall of the casing, is bent upwardly at 45, and is formed with a horizontal portion 10 in which is mounted an adjustable screw tube 47 that is retained in its adjusted position by the nut 48. Coupling 22 is also provided with a tubular projection 49, the bore of which extends entirely through the coupling, and on this tubular end is secured a 15 stop plug 50 which supports a coupling 51 to which is connected the upper end of said heater coil, as shown at 52.

A double valve casing 53 is located on the 20 outside of the heater casing and is connected to coupling 51 by a pipe 54, and diametrically opposite to said pipe 54, said casing 53 is provided with a port 55 which is in connection with the interior of valve casing 56.

Casing 53 is formed with a valve seat 57 25 directly below port 55 and a second seat 58 at its lower end and has a main water inlet 59 which is adapted to be connected to any source of water. Within casing 53 is positioned valves 60 and 61 which seat respectively on seats 57 and 58. These valves are secured to a single stem 62, and are positioned relative to each other, that when either one is closed the other is open. Stem 30 35 40 projects upwardly through a stuffing box 63 and its upper end is reduced in diameter to slidably engage within the bore of screw 47. Intermediate said screw 47 and stuffing box 63, said stem is provided with a nut or nuts 64, on each side of which is mounted the springs 65 and 66, the spring 65 being of less strength than spring 66 for reasons hereinafter set forth. On the top of spring 66 is mounted a flanged cap 67 which is 45 adapted to contact with the lower end of screw 47.

Connected to the lower side of valve casing 53 and extending downwardly through a stuffing box 68, is a pipe 69 which connects 50 at its lower end with one end of a piston chamber 70 whose opposite end is connected with valve casing 56 by a pipe 71, said casing being formed with a valve seat at the top end of pipe 71 which is adapted to 55 operate with a regulating valve 72 to regulate the flow of water to the heater coil. Piston chamber 70 is a closed chamber having a piston valve 73 therein whose normal position is intermediate the pipes 69 and 60 71. Valve 73 is fixed upon a piston rod 74 whose inner end is supported and guided in a projecting lug 75 fixed to the rear wall of chamber 70, and whose outer end extends through a suitable stuffing box 76 and is secured to the long end of a lever 77, pivoted 65

at 78 to a casing 79, in which is contained the gas valves 80 and 81.

Casing 79 contains a gas inlet chamber 82, a supply chamber 83, and a main burner chamber 84, the latter being connected, 70 through pipe 85, to a burner ring 86 which communicates with and furnishes gas to a plurality of main burners 87, two only being shown in the drawing.

Valve 81 controls the flow of gas from chamber 82 to chamber 84 and is operated to an open position, by the short arm 88 of lever 77 engaging the projecting end of the valve rod 89 of valve 81, and is closed by a spring 90 when the force of the lever is removed from the opposite side.

Valve 80 controls the flow of gas from chamber 82 to chamber 83 and is operated to an open position by a lever 91 which engages its stem 92 and is returned to a closed position by a spring 93. Lever 91 is pivoted at its lower end to a bracket 94 and is provided with a sharp-edged lug 95 which engages the lower free end of a lever 96 which is pivoted at its upper end to a bracket 97 secured to the wall of the heater body. Lever 96 is operated in one direction by a thermostatic rod 98 whose free end contacts therewith adjacent its pivot, and said thermostatic rod has its opposite end fixed in a bracket 99 secured to the side wall of the heater and on the interior thereof. This thermostatic rod 98 is mounted above a pilot burner 100 which has pipe connections with chamber 83 of casing 79.

Piston chamber 70 is supported in any suitable manner, and in the present instance it is shown provided with a depending lug 101 which engages a recess formed in the top side of bracket 97.

In operation, assuming that the several parts of the apparatus are in the position shown in the drawing, the pilot burner 100 is first lighted. This is accomplished by manually operating lever 96 to open valve 110 80, so that gas from main supply inlet 102 can flow into pilot inlet 103 and thence to the burner. Lever 96 is held in the open position for a short period after the pilot burner has been lighted, or until the heat from the burner expands the thermostatic rod sufficiently to hold the valve open. The pilot burner is kept continuously burning, and should it be accidentally extinguished, rods 98 would contract and allow the spring 120 93 to close the valve 80 which would cut off the supply of gas.

All of the water pipes being full of water, the pilot burner lighted, and the main burners not lighted, by opening the outlet end 125 of the system will cause the water to flow from the main water inlet 59 into casing 53, down pipe 69 into chamber 70, which would force piston 73 to the left, then upwardly through pipe 71 and horizontally through 130

casing 53 and into the coil at 52. From the lower end of the coil the circulation would continue through pipes 35 and upward through central pipe 21, on all sides of the 5 thermostat, and then through the outlet pipe 103 to the discharge. During the flow of water, the piston 73 having been moved to the left, it has operated lever 77, which has in turn opened valve 81, so the gas is then 10 supplied to the main burners 87 and are ignited from the flame of the pilot burner, which as before stated, is kept continuously burning. Thus the main burners heat the coils and the water therein as fast as it flows 15 therethrough, consequently, in a moment, hot water is supplied at the discharge end of the system. The moment that the discharge end is closed, the circulation of water through the heater is stopped, and this releases the pressure from the right hand side 20 of piston 73 and it is at once forced to the right by the spring 90 of valve 81 and then closes the admission of gas to the main burners and extinguishes the lights and consequently 25 reduces the supply of heat to the coil.

It will be observed that valve 80 controls the supply of gas to both the pilot and main burners and as before stated, should the 30 pilot burner be accidentally extinguished, the total supply of gas would be cut off. This avoids wasteful and dangerous escape of gas through the pilot burner and main burners. In other words, the main burners 35 cannot be lighted until the pilot burner is first lighted. It will also be observed, that piston 73 is slightly smaller than the diameter of its chamber so that a by-pass is formed around its periphery, to allow its 40 free movement to the right under the influence of spring 90 when the water pressure is reduced. It will thus be seen that the flow of water through the heater only controls the admission of gas to the main burners and has no effect upon the temperature 45 of the water discharged therefrom, excepting to furnish water as hot as the heat from the burners will make it.

To regulate the degree of temperature of the water discharged, the flow of cold water to the heater and gas to the burners is controlled by the thermostatic member 38 and its connections and they operate as follows:—When the discharge end of the system is opened and water is flowing through tube 21, in contact with the thermostatic rod 38, the temperature of the water affects said rod and causes it to expand and contract according to the degree of temperature. If the water is sufficiently hot to expand the rod, its upper end operates lever 42 and causes it to depress valve rod 62 which will close valve 61 and open valve 60. This will cut off the flow of cold water 65 downwardly from inlet 59, and conse-

quently release the pressure in chamber 70, which will cause valve 81 to close and extinguish the main burners, and at the same time allow the cold water to flow upwardly from inlet 59 and then directly into the coil 70 to reduce the temperature of the water flowing therethrough. As the water gets cooler, rod 38 contracts, the flow of water is again reversed and the main burners are again lighted.

75

The temperature of water desired, is secured by adjusting screw 47 which will regulate the throw of valves 60 and 61, that is, if water of high temperature is desired, screw 47 is adjusted upwardly so that it 80 would take a long expansion of rod 38 to open valve 60, but if cooler water is desired the screw is adjusted downwardly. Upon the contraction of rod 38, valve 60 is returned to its seat by the light spring 85 65 and when said valve is open and valve 61 is closed, heavy spring 66 will absorb all surplus pressure that may occur due to excess expansion of rod 38.

From the above description, it will be 90 noted that a heater is provided wherein any temperature of water can be obtained at the discharge end with a minimum of variation, and this is accomplished by controlling the operation of a double valve by a thermostatic 95 means, and at the same time without reversing the flow of water through the heating coil. Basin 14 will receive the condensation from the heat and is provided with a suitable aperture 104 from which 100 to draw said water of condensation, and it will be further understood, that a cover or deflector can be mounted over thermostatic member 98 and pilot burner to prevent the water of condensation from extinguishing 105 the pilot burner light.

Having thus fully described the invention, what is claimed is:—

1. In a heater of the character described, a water receptacle, a cold water inlet, two 110 branch supply pipes leading from said inlet to supply water to said receptacle, a motor connected in one of said branch supply pipes for operating a gas valve to open position, means for alternately opening said 115 branch supply pipes to said inlet to cause the water to flow solely through one branch pipe at one time to operate said motor to open said gas valve and at another time solely through the other branch pipe free 120 from said motor to allow the gas valve to close.

2. In a heater of the character described, a water receptacle, a cold water inlet embodying a casing provided with two outlets, 125 a branch supply pipe leading from each outlet to supply water to said receptacle, a motor connected in one of said branch supply pipes for operating a gas valve to open position, and a thermostatically operated means 130

- for alternately opening said branch supply pipes to said inlet to cause the water to flow solely through one branch pipe at one time to operate said motor to open said gas valve 5 and at another time solely through the other branch pipe free from said motor to allow the gas valve to close.
3. In a heater of the character described, a water receptacle, a cold water inlet embodying a casing provided with two outlets located in alinement with each other, a branch supply pipe leading from each outlet of the casing to supply water to said receptacle, a motor connected in one of said branch supply pipes for operating a gas valve to open position, and a thermostatically operated means for alternately opening said branch supply pipes to said inlet to cause the water to flow solely through one branch pipe at one time to operate said motor to open said gas valve and at another time solely through the other branch pipe free from said motor to allow the gas valve to close.
- 25 4. In a heater of the character described, a water receptacle, a cold water inlet, a valve-casing provided with two outlets located in alinement with each other, said inlet being connected to said casing between the two outlets, a branch supply pipe leading from each outlet to supply water to said receptacle, a motor connected in one of said branch supply pipes for operating a gas valve to open position, and a thermostatically operated means for alternately opening said branch supply pipes to said inlet to cause the water to flow solely through one branch pipe at one time to operate said motor to open said gas valve and at another time solely through the other branch pipe free from said motor to allow the gas valve to close.
5. In a heater of the character described, a water receptacle, a cold water inlet embodying a casing provided with two outlets in alinement with each other, a branch supply pipe leading from each outlet to supply water to said receptacle, a motor connected in one of said branch supply pipes for operating a gas valve to open position, a double valve in said casing, and a thermostatically operated means for operating said double valve to alternately open said branch supply pipes to said inlet to cause the water to flow solely through one branch pipe at one time to operate said motor to open said gas valve and at another time solely through the other branch pipe free from said motor to allow the gas valve to close.
6. In a heater of the character described, a water receptacle, a cold water inlet embodying a casing provided with two outlets in alinement with each other, a branch supply pipe leading from each outlet to supply water to said receptacle, a gas control-
- ling motor connected in one of said branch supply pipes, a double valve in said casing for engaging said outlets and provided with an extended stem, means on said stem for normally retaining said double valve in engagement with one of said outlets and free from the other, and a thermostatically operated means for operating said double valve to alternately open said branch supply pipes to said inlet.
7. In a heater of the character described, a water receptacle, a cold water inlet embodying a casing provided with two outlets in alinement with each other, a branch supply pipe leading from each outlet to supply water to said receptacle, a gas controlling motor connected in one of said branch supply pipes, a double valve in said casing for engaging said outlets and provided with an extended stem, means on said stem for normally retaining said double valve in engagement with one of said outlets and free from the other, means for regulating the throw of said double valve, and a thermostatically operated means for operating said double valve to alternately open said branch supply pipes to said inlet.
8. In a water heater of the character described, a receptacle, a cold water inlet embodying a casing provided with two outlets in alinement with each other, a branch supply pipe leading from each outlet to supply water to said receptacle, a gas controlling motor connected in one of said supply pipes, a double valve in said casing for engaging said outlets and provided with an extended stem, means on said stem for normally retaining said valve in engagement with one of said outlets, a thermostatically operated means for operating said valve to alternately open said supply pipes to said inlet, and means also on said stem for taking up the excessive pressure of said thermostatically operated means.
9. In a heater of the character described, a water receptacle, a cold water inlet embodying a casing provided with two outlets in alinement with each other, a branch supply pipe leading from each of said outlets, a gas controlling motor connected in one of said branch supply pipes, a valve in said casing for alternately engaging said outlets and provided with an extended stem, means on said stem for normally retaining said valve in engagement with one of said outlets, and a thermostatically operated means for operating said valve and embodying a thermostatic rod located within said water receptacle in the path of the out-flowing water.
10. In a heater of the character described, a water receptacle provided with a casing, a cold water inlet therefor, branch supply pipes connected to said inlet to supply water to said receptacle, a gas controlling mo-

tor connected in one of said branch supply pipes, a valve for alternately closing said branch supply pipes, a lever for operating said valve pivoted within said casing, and a 5 thermostatic rod in the path of the out-flowing water for operating said lever.

In testimony whereof I affix my signature in presence of two witnesses.
